CRIBBING

Filed Nov. 5, 1931

21 42 Inventor:
Earl C. Alexander
By Williams, Bradbury,
the Caleb E. Hinckley, Atty.

UNITED STATES PATENT OFFICE

EARL C. ALEXANDER, OF GLEN ELLYN, ILLINOIS, ASSIGNOR TO MASSEY CONCRETE PRODUCTS CORPORATION, OF CHICAGO, ILLINOIS, A CORPORATION OF VIRGINIA

CRIBBING

Application filed November 5, 1931. Serial No. 573,169.

The present invention relates to cribbing and is particularly concerned with the provision of an improved cribbing of the closed face, flush type which has advantages that are not present in the cribbings of the prior art.

One of the most popular forms of cribbing employs concrete members alternately and transversely laid upon each other, the stretchers consisting of members of regular rectangular cross section and the headers being provided with T-shaped formations for retaining the stretchers in place. One of the disadvantages of a cribbing of this type lies in the fact that there are spaces or openings in the forward cribbing wall through which the backfill may be washed out and the T-shaped formations on the headers project beyond the front stretcher wall where they are exposed in such manner that the interlocking formations might be broken off. Furthermore, such a cribbing does not present a finished appearance and one of the objects of the present invention is the provision of an improved form of cribbing having a substantially closed face and having a flush type face in which there are no projecting headers nor exposed interlocking formations.

Another object of the invention is the provision of an improved front stretcher unit which is adapted to be used with certain cribbings to transform the cribbings from the open and projecting header type to the closed face and flush type.

Another object of the invention is the provision of an improved cribbing assembly in which the stretchers interlock with the headers and prevent the headers from moving in a lateral direction, and in which the headers prevent movement of the stretchers in a direction transverse to the face of the wall.

Another object of the invention is the provision of an improved cribbing having a front wall formed of members of regular rectangular formation with drainage slots which are substantially concealed so that the front cribbing wall presents the finished appearance of a wall of masonry.

Other objects and advantages of the in-

vention will be apparent from the following description and from the accompanying drawing, in which similar characters of reference indicate similar parts of the several views.

In the drawing:

Figure 1 is a view in perspective of one of the improved stretcher units;

Figure 2 is a front elevational view of a portion of a cribbing wall constructed according to the present invention;

Figure 3 is a transverse sectional view taken on the plane of the line 3—3 of Figure 2; and

Figure 4 is an end view of another modification of the front stretcher unit.

The improved stretcher unit shown in Figure 1 is indicated in its entirety by the numeral 10 and all of the units of the present cribbing are preferably pre-cast concrete members which are provided with reinforcement 11, 12. The reinforcement of cribbing members of this type will be evident to one skilled in the art and therefore will not be described in detail.

The front stretcher unit 10 preferably consists of a precast concrete member having a substantially plane face 13 of substantially rectangular form and substantially plane upper and lower bearing surfaces 14, 15. The ends 16, 17 may also be provided with substantially plane surfaces adapted to abut against the similar surfaces on adjacent front stretchers.

The face 13 preferably is provided with beveled surfaces 18 at its boundary and the lower bearing surface 15 is preferably provided with a narrow slot 19, the depth of which preferably corresponds to the projection of the beveled surface 18 on the face 13. The slot 19 thus terminates at the line 20 which is also the corner of the beveled surface 18, and this makes the slots less perceptible in the front cribbing wall. The slots 19 are sufficiently deep to permit drainage but the natural angle of repose of the backfill is such that none of the backfill could appear at the front end of the slot 19 and the backfill is not washed out of the slot to any substantial degree.

The depth of the stretcher unit 10 from the lower bearing surface 15 to the top bearing surface 14 preferably corresponds to the combined depth of the header 21 and a rear 5 stretcher 22 so that one of the front cribbing units 10 may enclose and protect two courses of the rear cribbing units. Furthermore, the front stretcher units are intended to interlock with the header units 21 and to enclose and 10 protect the ends of the header units so that in order to provide a closed face cribbing the front stretchers must extend in a vertical direction far enough to cover the space between the headers 21 and cover the ends of the 15 headers 21.

The front stretcher unit 10 is also provided with rearwardly extending integral bodies 23, 24 for the purpose of interlocking with the headers 21 and the bodies 23, 24 are preferably provided with sockets 25, 26 in their 20 upper and lower surfaces, for the purpose of receiving the vertically projecting lugs 27, 28, carried by the headers 21. In order to save material, the rearwardly extending 25 flanges 23, 24 need not be continued from end to end of the stretcher unit 10 but may be terminated at the diagonal surfaces 29, 30 and the intermediate portion of the stretcher unit 10 may be narrower, being defined by 30 the substantially plane surface 31 at the rear.

The thickness of the flanges 23, 24 between its upper surface 32 and lower surface 33 preferably corresponds to the vertical depth of one of the rear stretchers 22 and the depth 35 of the sockets 25, 26 is such that these sockets accommodate the vertically extending lugs 27, 28 on the headers 21. In the embodiment shown in Figure 1 the flanges 23, 24 are located at the top face of the stretcher unit 10 40 so that the upper surface 32 of the flange 23 is flush with the upper bearing surface 14. However, it is also possible to locate the rearwardly extending flanges 23, 24 at any desired point between the upper and lower 45 bearing surfaces 14 and 15, at the bottom of the stretcher unit or midway between the bottom and top of the stretcher unit as shown in Figure 4.

The vertically extending lugs on the headers 21 are preferably substantially rectangular in section and provided with the rear beveled surfaces 34 which are adapted to engage the beveled surface 35 in the socket 25 or 26. The sockets 25, 26 may be made with a suitable 55 clearance for a substantial fit with the lugs 27, 28 particularly in the case where front stretcher units 36 are also employed. The header units 21 are preferably located at the crack between the ends of two adjacent front stretcher units 10, so that two front 60 stretcher units in each course are locked in place by each header unit and, consequently, the width of the socket 25 from the end 17 to the flat surface 37 corresponds to one-half 65 the horizontal width of the headers 21.

Referring to Figure 3, this is a sectional view of an exemplary installation and it will be observed that an ordinary foundation can be utilized or a plurality of stretchers 38-42 of simple rectangular cross section may be 70 employed as a substitute for the foundation. The foundation stretchers 38-42 are so located as to engage the lower surface of the front stretchers 10 and the lower surface of the lower header 21 below the front stretcher wall and below the rear stretcher wall. 75

A pair of headers 21 may be laid across the foundation 38-42 parallel to each other and at such a distance from each other that they will be located in the sockets 26 of a front stretcher unit 10 which is placed upon them. A front stretcher unit 10 may then be placed in front of the ends of the lowest header 21 with the upper lugs 27 in the sockets 26 and the cribbing walls may be made as long as desired by using any number of additional sections of headers and stretchers. The next header is supported upon transverse rear stretchers 22 and on the front stretchers 10 and 36 in the embodiment of Figure 3, but in some embodiments of the invention the front rectangular stretchers 36 may be wholly eliminated. The use of the front rectangular stretchers 36 increases the thickness of 85 the front stretcher wall and this is an example of the finishing of a cribbing of the square stretcher and T-header type with an additional flush type facing wall consisting of the stretchers 10. In such case the front wall 90 stretchers 10 need not be made so thick from front to rear as would otherwise be required and they may be made thinner than illustrated in Figure 3 so that the front stretchers 10 merely compose a covering for the ends of 95 the headers 21 and the stretchers 36. 100

When the stretchers 36 are eliminated the stretchers 10 may have their bodies made thicker to bear the weight of the front stretcher wall. 110

The top of the wall may be finished by a front stretcher 10 which does not have the socket 25 if desired, but economical construction may often dictate the use of identical headers 10, since the upper sockets 25 will merely be superfluous. The cribbing wall may be made as high as desired by using as many stretchers and headers as desired, care being taken to double up the headers and stretchers at the bottom if the height of the wall is such as to produce a weight excessive for the bearing surface and strength of single rows of headers and stretchers. It should also be understood that spacer blocks of the type shown in prior applications of the same company may be substituted for the rear stretchers 22 or the intermediate stretchers 36 and the cribbing wall may be made as deep from front to back as desired by employing additional rearwardly extending headers 21lapping over the rear stretchers 22 to provide ad- 115 120 125 130

ditional rear sections of the cribbing wall.

It will thus be observed that I have provided an improved facing unit for ordinary cribbings, which transforms an ordinary cribbing

6 into a closed face, flush type cribbing wall or my front stretcher unit may be utilized in a new cribbing assembly in which this unit is used to build up the front stretcher wall without additional front stretchers. The present

10 cribbing assembly has the ends of its headers protected and enclosed and the facing blocks or units are securely anchored in the cribbing assembly by their interengagement with the vertically extending lugs on the T-shaped

15 headers.

While I have illustrated and described a preferred embodiment of my invention, many modifications may be made without departing from the spirit of the invention, and I do not

20 wish to be limited to the precise details of construction set forth, but desire to avail myself of all changes within the scope of the appended claims.

Having thus described my invention, what 25 I claim is new and desire to secure by Letters Patent of the United States is:

1. A cribbing comprising a plurality of stretchers of simple rectangular cross section having plane sides and a plurality of headers 30 of substantially rectangular cross section having laterally projecting lugs at each end, said headers and stretchers being laid alternately and transversely upon each other to form a cribbing, and a facing wall comprising a multiplicity of facing cribbing members of sufficient size to engage each other and enclose and cover one wall of said cribbing, said facing members being provided with rearwardly extending flanges having 35 interlocking formation for interlocking engagement with said headers.

2. A cribbing comprising a plurality of stretchers of simple rectangular cross section having plane sides and a plurality of headers 45 of substantially rectangular cross section having laterally projecting lugs at each end, said headers and stretchers being laid alternately and transversely upon each other to form a cribbing, and a facing wall comprising a multiplicity of facing cribbing members of sufficient size to engage each other and enclose and cover one wall of said cribbing, said facing members being provided with rearwardly extending flanges having 50 interlocking formations for interlocking engagement with said headers, said facing units being provided with longitudinally extending slots to facilitate drainage of said cribbing.

60 3. A cribbing comprising a plurality of stretchers of simple rectangular cross section having plane sides and a plurality of headers 65 of substantially rectangular cross section having laterally projecting lugs at each end, said headers and stretchers being laid

alternately and transversely upon each other to form a cribbing, and a facing wall comprising a multiplicity of facing cribbing members of sufficient size to engage each other and enclose and cover one wall of said 70 cribbing, said facing members being provided with rearwardly extending flanges, said flanges being provided with vertically extending sockets located to receive vertically extending lugs on the headers. 75

4. A cribbing comprising a multiplicity of stretchers and headers, said stretchers and headers being provided with substantially plane rectangular bearing surfaces and being laid alternately and transversely upon each 80 other to form a cribbing, and a facing wall comprising facing blocks adapted to engage each other and form a substantially closed wall when assembled with said cribbing, said facing wall being provided with rearwardly 85 extending interlocking formations for engaging interlocking formations on said headers to secure said facing wall in place.

5. A cribbing comprising a multiplicity of stretchers and headers, said stretchers and 90 headers being provided with substantially plane rectangular bearing surfaces and being laid alternately and transversely upon each other to form a cribbing, and a facing wall comprising facing blocks adapted to engage 95 each other and form a substantially closed wall when assembled with said cribbing, said facing wall being provided with rearwardly extending interlocking formations for engaging interlocking formations on said headers to secure said facing wall in place, said facing blocks being equal in vertical depth 100 to the combined depth of one header and one stretcher.

In witness whereof, I hereunto subscribe 105 my name this 2 day of November, 1931.

EARL C. ALEXANDER.
